UNITED STATES PATENT OFFICE

LARS L. FURAN, OF THIEF RIVER FALLS, MINNESOTA

TURNING SIGNAL

Application filed August 23, 1928. Serial No. 301,593.

The invention aims to provide a new and improved turning signal for motor vehicles, which may be easily and inexpensively manufactured and marketed, readily installed, and conveniently operated to show when a turn is to be made.

A further object is to provide a construction in which a portion of the signal may take the form of a plate to display the name 10 of the city or town which is the residence of the owner.

A still further aim is to provide a construction in which a pointer and actuator therefor are shaped to jointly form a simulation 15 of a human hand with the index finger extended.

With the foregoing in view, the invention resides in the novel subject matter herein-after described and claimed, description being 20 accomplished by reference to the accompanying drawings.

Figure 1 is a front elevation showing the signal retracted;

Fig. 2 is a top plan view of the signal, a 25 portion of the machine by which it is carried, being shown in horizontal section;

Fig. 3 is a front elevation with the signal extended;

Fig. 4 is a top plan view with the parts 30 related as in Fig. 3;

Fig. 5 is a transverse sectional view on line 5—5 of Fig. 3.

In the drawing above briefly described, the numeral 6 denotes a horizontally elongated support or base plate adapted to be secured by fastening means 7 to any desired part of an automobile body, preferably in front of the driver's seat. Pivoted for vertical swinging to the plate 6, is a link 8. Parallel with and spaced from this link, is a lever 9 of greater length than said link, said lever being fulcrumed at 10 to the plate 6, at a point disposed at one end of said lever and spaced horizontally from the link pivot.

Two horizontally elongated plates 11 are shown disposed at opposite sides of the link 8 and lever 9. One end of these plates 11 is pivoted at 12 to the free end of the link 8.

By another pivot 13, portions of the plates 11 50 near their other end, are pivoted to the lever

9 between the ends of the lever. A pointer 14 is pivoted at 15 to the aforesaid other end of the plates 11, and an actuator 16 has one of its ends pivoted at 17 to this pointer, the other end of said actuator being pivoted at 55 18 to the free end of the lever 9.

While the plates 11 are preferably of sufficient size to act as name plates and to obscure the parts 8—9—14—16 when the signal is retracted, they function primarily as links 60 connecting the link 8 and lever 9 for parallel relation, and as supporting means for the pivot 15 of the pointer 14. The actuator 16 acts primarily as a link for projecting the pointer 14 when the parts are moved to the 65 position of Figs. 3 and 4, but a portion of this actuator 16 is preferably so shaped to simulate the lower or little finger portion of a clenched hand and a portion of the pointer 14, is preferably so shaped as to simulate the 70 upper or thumb portion of a clenched hand with the index finger extended, so that said portions of the actuator and pointer jointly form a simulation of a complete, clenched human hand with the index finger projected to a pointing position, when the signal stands as in Fig. 3.

The pivotal connection between the link 8 and the plate 6, is preferably formed by a rock shaft 19 which is secured to said link and 80 passes rotatably through an opening in the plate 6. This shaft is also intended to pass rearwardly through the portion 20 of the machine to which the plate 6 is secured, and the rear end of said shaft is provided with a crank or the like 21, by means of which it may be turned to move the signal from the retracted position of Figs. 1 and 2 to the projected position of Figs. 3 and 4, or vice versa. 85 Only one fastener such as 7 is necessary for securing the plate 6 to the machine, as the shaft 19 in passing through the part 20, holds said plate against any pivotal movement about said fastener.

Not only is the novel construction herein shown, of simple and inexpensive nature, but it is easy to operate, gives a distinct turning warning, and is generally desirable.

The details disclosed are preferably fol-

lowed but within the scope of the invention as claimed, variations may be made.

I claim:

1. A turning signal comprising a base, a link pivoted to said base for swinging in a vertical plane, a lever longer than said link, said lever being fulcrumed at one of its ends to said base for movement in the same directions as said link, the lever fulcrum and the link pivot being horizontally spaced, a substantially horizontal link pivoted at one of its ends to the free end of said link and pivoted at a point spaced from its other end to said lever, said point being located between the ends of the lever, a pointer pivoted to said other end of said horizontal link, a pointer-projecting link pivoted to the free end of said lever and to said pointer, whereby the pointer may be swung upwardly and laterally to a projected position beyond the end of said horizontal link and inwardly and downwardly to a position behind said horizontal link when the latter is swung upwardly and laterally by said first named link and means for swinging the first-named link.
2. A structure as specified in claim 1; the pivotal connection between the first-named link and the base being in the form of a rock shaft secured to said link, said means for swinging said link consisting of a crank secured to said rock shaft.
3. In a signal, a pointer and an actuator pivotally connected with each other and both shaped to jointly form a simulation of a human hand when the pointer is extended.
4. A structure as specified in claim 1, wherein said horizontal link is in the form of a name plate and adapted to obscure the pointer and pointer-projecting link from view when said pointer and link are in retracted positions.
5. In a signal, a flat pivotally mounted pointer plate having a portion shaped to simulate the upper or thumb portion of a clenched hand with the index finger only extended in a pointing position, and a flat actuating plate lying against and pivotally connected with said pointer plate, a portion of said actuating plate being shaped to simulate the remainder of a clenched hand, said hand-simulating portions of the two plates being normally out of co-operative hand-simulating relation with each other, and means for moving said plates about their pivots to a projected position in which said hand-simulating portions thereof co-act in producing the shape of a clenched hand with the index finger only extended in a pointing position.

In testimony whereof I have hereunto affixed my signature.

LARS L. FURAN.
